UNITED STATES PATENT OFFICE.

EDWARD PERRY WALKER, OF KANSAS CITY, MISSOURI.

ATTACHMENT FOR ELEVATOR-DOORS.

SPECIFICATION forming part of Letters Patent No. 357,430, dated February 8, 1887.

Application filed July 7, 1886. Serial No. 207,360. (No model.)

To all whom it may concern:

Be it known that I, EDWARD PERRY WALKER, of Kansas City, in the county of Jackson and State of Missouri, have invented 5 a new and useful Improvement in Attachments for Elevator-Doors, of which the following is a specification.

My invention is in the nature of an attachment for the top and bottom doors of an ele- 10 vator-shaft, the said attachment being designed to effect by the movement of the elevator-car the automatic operation of the doors of the shafts, so that the elevator-man is relieved of this duty.

15 The invention consists in the peculiar construction and arrangement of parts, which I will now proceed to describe.

In the accompanying drawings, Figure 1 is a front elevation of an elevator-door, showing 20 my improvements applied, the door being shown open in full lines and closed in dotted lines. Fig. 2 is a perspective view of the slide-bar and guide.

A represents the sliding door of the ele- 25 vator-shaft, which door is mounted upon rollers that travel upon guide-rails, as usual. To one side of the door is attached a rope, a, that passes around a pulley, b, on the elevator-shaft, and over another one, b', above, then passes 30 down to and connects with a slide-bar, B, in a vertical guide, C, which slide-bar has a foot, B', that projects horizontally into the path of the elevator-car, so that as the car nears the end of its descent it strikes said foot and pulls 35 down the slide, and the movement of which latter pulls back the door A of the elevator-shaft from its position in front of the opening in the same.

To restore the door to its position or close 40 it again, a weight, G, is arranged upon the opposite side of the door-opening in the elevator-shaft, and is connected to two cords, c c', which pass, the one, c, over a pulley, d, and connects with the top of the door, while the other cord, c', passes around the two pulleys d' d'' and connects with the bottom of the door. 45 It will thus be seen that the gravity of weight G closes the door as soon as the car passes off

of the foot B' of the slide, the power of the weight being distributed by the two cords c 50 and c' to the top and bottom of the door, so as to prevent it from gripping, and cause it to move smoothly, certainly, and sensitively.

It will be seen from the foregoing description that the door of the elevator shaft is made 55 entirely automatic in its working, being opened by the descent of the car upon the foot B' and closed again by the weight as soon as the car rises, or passes off of the foot B'.

As so far described the attachment is ap- 60 plicable only to the bottom door of the elevator-shaft; but it is obvious that the same arrangement is applicable to the top door by simply reversing the position of the slide and foot B B' and its attachment, and placing the 65 foot so as to be struck by the top of the car in ascending.

I am aware that the door of an elevator has been worked by mechanism in the car and a weight and pulley, and I do not claim this, 70 broadly.

Having thus described my invention, what I claim as new is—

1. The combination, with the horizontally-sliding door in an elevator-shaft, of the cord 75 or rope a, the guide-pulleys b b', the slide B, with foot B' projecting into the path of the elevator, the weight G, the pulleys d d' d'', and the cords c c', connected at one end to the weight and passing around the pulleys, and 80 connected, respectively, to the top and bottom of the door, substantially as shown and described.

2. The combination, with the sliding ele- 85 vator-door, of the weight G, the pulleys d d' d'', and the cords c c', connected at one end to the weight and passing around the pulleys, and connected, respectively, to the top and bottom of the door to distribute the power of the weight thereto and prevent gripping, as de- 90 scribed.

EDWARD PERRY WALKER.
